(57) **CLAIM**

The ornamental design for a exercise device, as shown and described.

DESCRIPTION

FIG. 1 is a perspective view of a exercise device, showing the new design;

FIG. 2 is an exploded perspective view thereof;

FIG. 3 is an exploded front elevational view of FIG. 2, the rear elevational view being a mirror image thereof;

FIG. 4 is a top plan view of FIG. 2, the bottom plan view being a mirror image thereof;

FIG. 5 is a left-side elevational view thereof, the right-side elevational view being a mirror image thereof;

FIG. 6 is a right-side elevational view of a left handle thereof, a tube and a right handle omitted for clarity of illustration;

FIG. 7 is a left-side elevational view of the right handle thereof, the tube and the handle omitted for clarity of illustration;

FIG. 8 is a left-side elevational view of the tube thereof, the right handle and left handle omitted for clarity of illustration;

FIG. 9 is a right-side elevational view of the tube, the right handle and left handle omitted for clarity of illustration; and,

FIG. 10 is an enlarged perspective view of the left and right handles mutually joined in a configuration that does not include the tube.

The broken lines in FIGS. 7 and 8 depict unclaimed portions of the design.
